KILOWATT HOUR METER BASE COVER

Richard S. Jones, Bountiful, Utah, assignor to Sentinel
Lighting & Manufacturing Company, Salt Lake City,
Utah

Filed Jan. 14, 1972, Ser. No. 218,043

Term of patent 14 years

Int. Cl. D10—04

U.S. Cl. D52—6 R

FIG. 1.

FIG. 2.

FIG. 4.

FIG. 3.

FIG. 5.

FIG. 6.

FIG. 7.

FIG. 8.

FIG. 10.

FIG. 9.

FIG. 11.

FIG. 12.

FIG. 1 is a front perspective view of a kilowatt hour meter base cover showing my new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof;

FIG. 7 is a bottom plan view thereof;

FIG. 8 is a sectional view of FIG. 2 as taken from line 8-8;

FIG. 9 is a sectional view of FIG. 2 as taken from line 9-9;

FIG. 10 is a sectional view of FIG. 2 as taken from line 10-10;

FIG. 11 is a sectional view of FIG. 2 as taken from line 11-11;

FIG. 12 is a sectional view of FIG. 2 as taken from line 12-12.

I claim:

The ornamental design for a kilowatt hour meter base cover, as shown and described.
